LOW-TEMPERATURE CHAMBER
REFRIGERATION

Erwin Lodwig, Franklin Square, N. Y., assignor to
Mobile Refrigeration, Inc., New York, N. Y., a
corporation of New York

Application May 28, 1942, Serial No. 444,800

6 Claims. (Cl. 62—102)

1

This invention relates to refrigeration and more particularly concerns improved apparatus for rapidly cooling the atmosphere in a chamber to very low temperatures.

In the development and testing of aircraft, parts thereof, and instruments and other apparatus for use thereon, it is necessary to subject various parts and devices to the extreme conditions of atmospheric temperature and pressure encountered in flight. These conditions include temperature changes from the highest ground temperature to temperatures well below 100 degrees below zero Fahrenheit, and pressure changes from normal atmospheric pressure at sea level to less than four inches of mercury absolute. Since the conditions to be reproduced include sub-atmospheric pressures, a closed chamber must be used, and in order that the operation of the instruments or devices may be observed, a window or sight opening is preferably provided in the chamber.

In the operation of a chamber under the conditions described, the formation of frost is a serious problem. Moisture is condensed from the air within the chamber as its temperature is lowered below the dew point of the air, and freezes on the evaporators or other surfaces employed to cool the chamber. Further, it is frequently necessary to open the chamber while the atmosphere therein and the interior surfaces thereof are at very low temperatures, and under such conditions, frost quickly accumulates on the cold interior surfaces of the chamber, including the inner surfaces of any windows or sight openings therein. This frosting is caused by the entry of air at room temperature and relative humidity and the sudden condensation and freezing of moisture from such air when its temperature is lowered by mixture with the cold air and contact with the cold surfaces within the chamber. The frost both obscures the sight opening and reduces the efficiency of the cooling surfaces by partially insulating them from the air within the chamber so that the rate of cooling of the chamber air is retarded and it is impossible to accurately observe the operation of devices in the chamber through the window.

With the above and other considerations in mind, it is proposed in accordance with the present invention to devise an improved chamber having cooling means capable of rapidly lowering the temperature of the air in the chamber to very low values without producing frost accumulations that either obscure a window in the chamber or substantially retard the rate of cooling of the

2

chamber air. I have found it desirable in chambers of the type described to provide separate refrigerant evaporating means for respectively cooling the walls of the chamber and the air in the chamber. I have further discovered that by circulating the air in the chamber successively over the separate evaporating means but at a higher velocity over the air cooling evaporator than over the wall cooling evaporator means, accumulations of frost or ice may be removed from the air cooling evaporator, and the accumulation of frost on that evaporator when the chamber is closed may be avoided. I have also discovered that accumulations of frost may be quickly removed from the inner surface of a sight opening or window in the chamber by successive circulation of air in the chamber over the window and the cooled chamber walls.

Other objects, advantages, and features of the invention will be apparent from the following description of a typical embodiment thereof which is illustrated in the accompanying drawing.

In the drawing

Fig. 1 is a sectional elevation illustrating a refrigerating chamber provided with cooling means and embodying my invention;

Fig. 2 is a sectional view of the air cooling evaporator taken along the line 2—2 of Fig. 1 and viewed in the direction of the arrows; and

Fig. 3 is a sectional view on a reduced scale of one of the wall evaporators of the chamber illustrated in Fig. 1.

Refrigerated chambers embodying the invention may be of any desired form and are usually rectangular or cylindrical. The chamber illustrated in the drawing is rectangular and its six surfaces comprise a door D and five wall sections, of which four are illustrated in Fig. 1 at W, W₁, W₂, and W₃. Since the chamber is substantially completely evacuated in use, its walls must be strong enough to withstand substantially full atmospheric pressure. This could be accomplished by constructing the walls of heavy gauge metal, but I prefer instead to employ wall sections formed of two spaced metal plates or sheets having passages therebetween. This arrangement provides walls having the requisite strength and relatively little mass, whereby the heat load imposed by the walls is reduced. The arrangement also provides passages between the wall plates so that the wall sections comprise evaporators in which refrigerant may be evaporated to cool the walls, and, to some extent, the air in the chamber.

In the illustrated embodiment, each wall section comprises two spaced metal plates 4 and 5

connected along their edges by edge spacers 6 and at intermediate points by reinforcing baffle spacers 7. The baffle spacers 7 are preferably staggered as shown in Fig. 3 to provide a circuitous passage between the wall plates for the flow of refrigerant. The edge spacers 6 are welded or otherwise tightly sealed to the wall plates 4 and 5 so that each wall section forms a sealed refrigerant evaporator. The several wall sections W, W₁, W₂, etc., may be of identical construction and are welded together along their meeting edges to form an air-tight chamber. Instead of using the spacers 6 and 7, the plates 4 and 5 may be offset or embossed to provide meeting areas that define circuitous refrigerant passages between the plates. The outer surfaces of the chamber walls may be heat insulated by any suitable material, and such insulation has been diagrammatically represented at 14.

The chamber door D may be of any suitable construction, and as shown covers substantially all of one surface of the chamber. The door D may be hingedly secured to a frame or flange 8 around the door opening, and may be held closed by suitable clamps or latches, not shown. A sight opening or window O is preferably provided in the chamber door D, and as shown may comprise a plurality of spaced glass panes 9 and 10 sealed in the frame 11 of the door. Spaced gaskets 12 and 13 may be provided between the door frame 11 and the chamber opening flange 8 to insure a tight closure.

An evaporator E is provided within the chamber for cooling the air therein and the instruments or other apparatus under test or observation. In accordance with the present invention, means are provided for circulating air in the chamber successively over this evaporator and the inner surfaces of the chamber wall section evaporators W, W₁, W₂, etc. The arrangement is such that the velocity of the circulated air passing over the evaporator E is considerably higher than that of the air passing over the chamber wall surfaces. In the disclosed embodiment, the evaporator E comprises a coil 15 having vertically disposed heat conducting fins 16 thereon, and the finned coil unit is enclosed in a flue or duct 17. The flue 17 has a fan compartment 18 below the evaporator coil 15 and in communication therewith through an opening 19. An air inlet opening 20 is provided in the front wall of the flue 17, and an outlet opening 21 is provided in the front wall of the fan compartment 18. A fan or blower 22 of any suitable construction is disposed to propel air at relatively high velocity through the flue 17, and as shown this fan is disposed adjacent the outlet opening 21 of the fan compartment 18. The fan 22 may be driven by an electric motor 23.

The assembly comprising the evaporator E and flue 17 is preferably spaced from the window O and may be disposed as shown adjacent the back wall section W₁ of the chamber with the air inlet and outlet openings 20 and 21 directed toward the opposite wall of the chamber, in the illustrated embodiment toward the chamber door D.

The evaporator coil 15 and the wall section evaporators are supplied with refrigerant from any suitable source such as a refrigerant compressing and condensing unit, conventionally represented at 25. The coil 15 of the evaporator E may be supplied with condensed refrigerant through a pipe 26, and evaporated refrigerant may be returned from the coil to the unit 25

through a suction line 27. Condensed refrigerant may be similarly supplied to the several wall section evaporators through the ducts 28, 29, 30, and 31, and evaporated refrigerant is returned therefrom to the unit 25 through suction lines 32, 33, 34, and 35. It should be understood that the unit 25 will include suitable known expansion valves and thermostatic controls to regulate the supply of refrigerant to the several evaporators in accordance with conventional practice.

In the operation of the illustrated embodiment of my invention, considering first the cooling of the chamber and the air and equipment therein from room temperature to a low temperature required for test or development operations, the door D is closed and the refrigeration unit 25 and fan 22 are started. Due to the arrangement of the flue 17, the air propelled by the fan 22 is confined to a path closely adjacent the coil 15 and fins 16 of the evaporator E and flows at a relatively high velocity over these parts, whereas as the air is circulated at lower velocities over the inner surfaces of the chamber walls and the pane 9 of the window O. Refrigerant evaporates in the chamber wall sections W, W₁, W₂, etc., and rapidly withdraws heat therefrom, thereby reducing the chamber wall temperature. At the same time, the evaporator E rapidly cools the air in the chamber, and the instruments and devices therein. As the cooling progresses, the temperature of the chamber walls falls below the dew point of the air in the chamber and below the freezing point, with the result that moisture is condensed from the air and frozen on the inner surfaces of the walls. The temperature of the evaporator E also falls below the dew point of the air and the freezing point of water, and the accumulation of frost on the evaporator coil 15 and fins 16 would also be expected. However, with the air flowing over the evaporator E at a considerably higher velocity than over the chamber walls, frost does not form on the evaporator E. The temperature of the instruments or other apparatus under test or observation in the chamber also falls below the dew point and the freezing point as these objects are cooled by the circulated air, but frost does not accumulate thereon.

The selective formation of frost on the chamber walls rather than on the evaporator E is apparently caused by the more rapid circulation of air over the evaporator which transfers heat thereto more rapidly than to the walls and accordingly maintains the evaporator at a somewhat higher temperature than the walls. Similarly the absence of frost on the apparatus under test in the chamber is believed due to the fact that such apparatus, being cooled by the circulated air, is at a higher temperature than the chamber walls. Regardless of the reason for this selective frost formation, the observed fact is that even after frost has accumulated on the surfaces of the evaporator E and on apparatus in the chamber, due to the opening of the chamber door D when the surfaces and apparatus are below freezing temperature, operation of the fan 22 with the door D closed rapidly removes not only the frost accumulated on the evaporator and the apparatus, but that formed on the inner surface of the glass pane 9 of the window O as well.

It is frequently necessary to open the chamber door D to give access to instruments or devices in the chamber while the air in the chamber, the apparatus therein, the evaporator E,

the inner surfaces of the chamber wall evaporator sections, and the inner pane 9 of the window O are at temperatures well below the freezing point. Before opening the door D, the fan 22 is stopped to avoid unnecessary heating by blowing chilled air out of the chamber. When the door D is opened, relatively warm moist room air enters the chamber and mingles with the cold air therein. The moisture introduced by the room air increases the relative humidity of the mixed air in the chamber to a point above saturation at the prevailing mixed air temperature with the result that immediate condensation takes place, forming a fog or mist in the chamber. The temperature of the chamber walls, the evaporator E, the inner surface of the glass pane 9 of the window O, and any apparatus under test in the chamber, are not only well below the dew point of the mixed air, but below the freezing point as well. Therefore, frost quickly forms on these surfaces within the chamber. The formation of frost on the pane 9 is particularly rapid, since with the door open, the cold pane is in direct contact with warm moist room air. The formation of frost on apparatus in the chamber prevents accurate observation thereof, particularly in the case of the dials or glass cover plates of indicating instruments, and if permitted to remain, such frost might impair the operation or accuracy of certain devices. When the chamber door D is again closed and the fan 22 started, the frost quickly disappears from the evaporator E and also from the inner surface of the window pane 9. At the same time, frost is quickly removed from the devices in the chamber. Removal of frost from the pane 9 and from the devices permits clear observation of the devices in the chamber. Defrosting of the evaporator coil E increases the rate at which heat is absorbed thereby from the chamber air. As a consequence, the chamber air temperature is quickly lowered to the desired value, the cooling of the instruments or devices in the chamber is not delayed, and the testing or development work proceeds rapidly.

It is my belief that the above described defrosting of the evaporator E, the window pane 9, and apparatus in the chamber involves a transfer of frost from these parts to the inner surfaces of the chamber wall evaporator sections W, W₁, W₂, etc., and results from the difference in temperature of the several parts and the successive circulation of air thereover. Since the air in the chamber is circulated at a higher velocity over the evaporator E than over the chamber wall evaporator surfaces, the evaporator E is maintained at a somewhat higher temperature than the chamber walls. The apparatus in the chamber which is cooled by the circulated air, is at a higher temperature than the chamber walls. Also, heat loss through the window structure O keeps the inner window pane 9 at a higher temperature than the chamber wall evaporator surfaces. It is therefore probable that the air circulating at relatively low velocity along the surfaces of the chamber wall evaporators is chilled to a temperature where moisture is condensed therefrom and deposited on these walls in the form of frost, reducing the moisture content of the air at this point. The air thus dried or dehydrated then passes over the surfaces of the evaporator E and the window pane 9, and over the apparatus under test in the chamber, its temperature is raised by contact with these

relatively warmer surfaces and its relative humidity is thereby decreased. The air then apparently picks up moisture from these surfaces by sublimation of the frost thereon. Although this explanation is believed correct, it should be understood that the invention is in no way dependent upon the accuracy thereof.

I claim:

1. In apparatus of the type described, in combination, a closed chamber having a window therein, at least two evaporators disposed at spaced points in said chamber and having surfaces exposed to the atmosphere therein, means for supplying refrigerant to said evaporators whereby their exposed surfaces are cooled, and means including an air propelling device for circulating some of the air within said chamber successively over said evaporators and said window and at a higher velocity over one of said evaporators than over the window and the other evaporator, whereby frost accumulations are removed from the window and from the evaporator over which the air is circulated at the higher velocity.

2. In apparatus of the type described, in combination, a closed chamber having at least a portion of its wall structure formed of metallic plates spaced to provide passages for the evaporation of refrigerant therebetween, an evaporator in said chamber spaced from the chamber wall structure, means for supplying refrigerant to said wall structure refrigerant passages and to said evaporator whereby said evaporator and the inner surfaces of said portion of said wall structure are cooled, and means including an air propelling device for circulating air in said chamber successively at high velocity over said evaporator and at a relatively lower velocity over the cooled inner surfaces of said portion of said wall structure, whereby accumulation of frost on said evaporator is avoided.

3. In apparatus of the type described, in combination, a closed chamber including a wall structure formed of metallic plates secured together and having passages for the evaporation of refrigerant therebetween, an evaporator in said chamber, means for supplying refrigerant to said evaporator and to said wall passages whereby said evaporator and the chamber wall structure are cooled, air propelling means in said chamber adjacent said evaporator and a flue closely enclosing said air propelling means and said evaporator and having openings therein spaced from said cooled wall structure for directing air propelled by said means successively at a high velocity over said evaporator and at a lower velocity over said cooled wall structure, whereby frost accumulations on said evaporator are removed.

4. In apparatus of the type described, in combination, a closed chamber including a wall structure formed of metallic plates secured together and having passages for the evaporation of refrigerant therebetween, an evaporator in said chamber, a window in said chamber spaced from said evaporator, means for supplying refrigerant to said evaporator and to said wall passages whereby said evaporator and the chamber wall structure are cooled, and means including an air propelling device for circulating air in said chamber successively at a high velocity over said evaporator and at a lower velocity over said cooled wall structure and said window, whereby frost accumulations are removed from said evaporator and said window.

5. In apparatus of the type described, in combination, a closed chamber including a wall structure formed of metallic plates secured together

and having passages for the evaporation of refrigerant therebetween, an evaporator in said chamber, a window in said chamber spaced from said evaporator, means for supplying refrigerant to said evaporator and to said wall passages whereby said evaporator and the chamber wall structure are cooled, air propelling means in said chamber adjacent said evaporator, and a flue closely enclosing said air propelling means and said evaporator and having openings therein spaced from said cooled wall structure for directing air propelled by said means successively at a high velocity over said evaporator and at a lower velocity over said cooled wall structure and said window, whereby frost accumulations on said evaporator and on said window are removed.

6. In apparatus of the type described, in combination, a closed chamber having an openable door therein, a window in said door, said chamber having a wall structure formed of spaced 20

metallic plates secured together and providing passages therebetween for the evaporation of refrigerant, an evaporator in said chamber spaced from said door, means for supplying refrigerant to said evaporator and to said wall structure refrigerant passages whereby said evaporator and the chamber wall structure are cooled, air propelling means adjacent said evaporator, and means for confining air propelled by said propelling means to a path closely adjacent said evaporator and for directing some of the air so propelled in an unconfined circulatory path successively over said cooled wall structure and said window, whereby air is circulated in said chamber at a higher velocity over said evaporator and at a lower velocity over said cooled wall structure and said window and frost accumulations are removed from said evaporator and said window.

ERWIN LODWIG.
